Primary Examiner—Cathron C Brooks*Assistant Examiner*—Deanna Fluegeman(74) *Attorney, Agent, or Firm*—Oliff & Berridge, PLC(57) **CLAIM**

The ornamental design for a computer operating apparatus, as shown and described.

DESCRIPTION

FIG. 1 is a front view of a computer operating apparatus;

FIG. 2 is a rear view thereof;

FIG. 3 is a side view thereof, the opposite side view being a mirror image; and,

FIG. 4 is a top view thereof, the bottom view being a mirror image.
